(57) **CLAIM**

The ornamental design for a self-defense key chain, as shown and described.

DESCRIPTION

FIG. 1 is a three-dimensional isometric view of a self-defense key chain showing the new invention;

FIG. 2 is a rear elevational view thereof.

FIG. 3 is a front elevational view thereof.

FIG. 4 is a right side elevational view thereof, the left side being a mirror image thereof; and,

FIG. 5 is a top plan view thereof, the bottom plan view being a mirror image thereof.

1 Claim, 5 Drawing Sheets

FIG. 1

FIG. 2

FIG. 3

FIG. 4

FIG. 5
